ATTORNEY.

UNITED STATES PATENT OFFICE.

URA M. BOYD, OF DALLAS, TEXAS.

TELEPHONE SIGNAL DEVICE.

1,211,534.

Specification of Letters Patent. Patented Jan. 9, 1917.

Application filed May 11, 1916. Serial No. 96,738.

To all whom it may concern:

Be it known that I, URA M. BOYD, citizen of the United States, residing at Dallas, in the county of Dallas and State of Texas, have invented certain new and useful Improvements in Telephone Signal Devices, of which the following is a specification.

Where telephones are used in public places considerable annoyance is often occasioned by persons who hold lengthy conversations and otherwise keep the telephone in use for a period in excess of that usually allowed, thus depriving others and interfering with the service.

For use in such places I have invented means for displaying a signal operated by the telephone when the receiver is moved from the hook-switch; said signal being of such a character as to attract the attention of the party about to use the phone and also notifying such party as to the limit of time he may use the telephone.

In carrying out the invention a support is provided and arranged to be attached to a telephone stand. A sliding member is carried in the support so as to rest on the switch-hook of the stand and to be elevated thereby when the receiver is removed from the hook. Arms have their lower ends pivoted to the upper end of the sliding member and are normally concealed by the support, but when the sliding member is elevated said arms are thrown out to each side as a signal. A suitable legend may be displayed on the arms. The sliding member is arranged to retract the arms when the receiver is replaced on the hook-switch.

It is quite evident that various structures might be evolved for carrying out this invention and the form described and shown is merely an example.

The invention will be more readily understood by reference to the accompanying drawings, wherein:

Figure 1 is an elevation of a portion of a telephone stand with the invention attached thereto, Fig. 2 is a rear elevation of the device, Fig. 3 is a side elevation of the arms and a vertical section of the support, and Fig. 4 is a cross-sectional detail.

In the drawings the numeral 1 designates a tubular support exhibiting a rectangular shape in cross-section. A sliding bar or plunger 2 is mounted in the support and is provided with a reduced lower end 3 extending from a shoulder 4 which normally

rests on a flange 5 at the bottom of the support, said flange and shoulder limiting the downward movement of the plunger. I wish to make clear that the plunger and the support may be correlated in other ways and it is not necessary that the support assume the form of a tube, but its office is to provide a support with which the plunger is slidably related.

At the top of the support an enlargement or shield 6 is provided. Target arms 7 are mounted behind the support with their enlarged outer ends or targets 8 normally concealed by the shield 6. These arms have their lower ends pivoted on a pin 9 passing through the upper end of the plunger. The arms normally stand one behind the other and each has a notch 10 cut in from one side so as to straddle a stud 11 on the back of the support. The support has sides 12 which terminate a short distance of the top of the plunger when the same is in its normal or lowered position.

The sides 12 hold the arms upright when the plunger is lowered and the stud prevents the arms passing the center when swung up. When the plunger is elevated the arms fall to each side and come to rest on the sides 12, assuming the position shown in dotted lines in Figs. 1 and 2. The stud acts to displace the arms laterally when the inclined edges of the notches ride thereover. When the plunger is lowered the ends of the arms are carried downward and are drawn over the upper edges of the sides, whereby they are swung upward as will be obvious.

A clamp member 13 is fastened to the lower portion of the support and extends laterally therefrom. The clamp is formed with a curved portion 16 constructed to fit the neck of a telephone stand and ears 14 project from this portion. The clamp is positioned so that when mounted on the stand the plunger 3 will have its lower end 2 resting on the switch-hook of the telephone stand as shown in Fig. 1, the support assuming an upright position. The clamp is fastened by a bolt 15 passed through the ears.

When the receiver is removed from the switch-hook and the latter springs upward, it will elevate the plunger 3 as shown in dotted lines in Fig. 1. When the plunger is elevated the arms 7 will be thrown out laterally which will attract the attention of the

person about to use the telephone. A suitable legend stating the limit of time for which the telephone may be used is displayed on the arms and their targets 8, in 5 any suitable manner. The face of the shield 6 may be used to display a hand pointing to the legend as shown, or other matter may be displayed on the shield. The arms will remain extended until the receiver is replaced 10 on the switch-hook whereby the plunger is lowered and the arms withdrawn.

It is obvious that one of the arms could be omitted and only one arm or an equivalent device used. The target or the entire 15 arm may be finished in a distinguishing color so as to be more conspicuous. It is to be understood that the invention may be embodied in various constructions so long as a relatively fixed support is correlated with 20 a movable member which is displaced by the switch-hook of a telephone stand to display a signal device on said stand.

What I claim is:

1. The combination with a telephone stand 25 and the switch-hook thereof, of a signal device comprising a support attached to the stand, a movable member carried by the support and displaced upwardly by the switch-hook, and a signal element normally dormant displayed by the movable member.

2. The combination with a telephone stand and the switch-hook thereof, of a signal device comprising a support attached to the

stand, a plunger correlated with the support and resting on the switch-hook whereby it 35 is displaced upward by the hook when the same is operated, and a target normally concealed by the support and having connection with the plunger whereby it is displaced laterally by the plunger when the latter is 40 displaced upwardly.

3. In a signal device for telephone stands, a support having means for attaching it to a telephone stand, and a normally dormant signal element carried by the support and 45 constructed to be displayed only when displaced laterally.

4. In a signal device for telephone stands, a support having means for attaching to a telephone stand, a relatively movable member 50 correlated with the support, and a normally concealed signal displayed when the movable member is displaced with relation to the support.

5. In a signal device for telephone stands, 55 an upright support, a laterally projecting clamp disposed on the support, a plunger mounted on the support, and a pair of target arms pivoted to the plunger, and means on the support for displacing the arms in opposite directions from each other as the plunger is moved upward.

In testimony whereof I affix my signature.

URA M. BOYD.
